UNITED STATES PATENT OFFICE.

WILLIAM G. LINDEMANN, OF MILWAUKEE, WISCONSIN, ASSIGNOR TO OZONE COMPANY OF AMERICA, OF MILWAUKEE, WISCONSIN, A CORPORATION OF DELAWARE.

OZONIZER.

1,363,000.

Specification of Letters Patent. Patented Dec. 21, 1920.

Application filed August 4, 1919. Serial No. 315,357.

To all whom it may concern:

Be it known that I, WILLIAM G. LINDEMANN, a citizen of the United States, and resident of Milwaukee, in the county of Milwaukee and State of Wisconsin, have invented new and useful Improvements in Ozonizers, of which the following is a description, reference being had to the accompanying drawings, which are a part of this specification.

10 The invention relates to ozonizers and more particularly to an ozonizer for generating ozone from a continuously flowing stream of compressed air.

15 One of the objects of this invention is to provide a construction in which large amounts of compressed air may be ozonized without producing high temperatures which affect both the production of ozone and the 20 electrodes.

25 A further object of the invention is to provide an ozonizer in which the ozonizing elements consists of a plurality of flat plates between which the compressed air to be ozonized is passed in an efficient manner.

30 A further object of the invention is to provide an ozonizer in which the ozonizing air is given a free passage through the ozonizer and at the same time is brought into the 35 zones of electric discharge so as to be efficiently ozonized.

35 The invention further consists in the several features hereinafter set forth and more particularly defined by claims at the conclusion hereof.

40 In the drawings: Figure 1 is a vertical sectional view through an ozonizer embodying the invention; Fig. 2 is a plan view of the ozonizing apparatus with the cover removed and parts broken away; Fig. 3 is a detail sectional view taken on the line 3—3 of Fig. 2; Fig. 4 is a vertical sectional view showing an ozonizer similar to Fig. 1, except for the outer casing; Fig. 5 is a section 45 taken on the line 5—5 of Fig. 4; Fig. 6 is a section taken on the line 6—6 of Fig. 4.

45 Referring to Figs. 1 to 3 inclusive, the numeral 6 designates a rectangular metal box or outer casing provided with a removable 50 metal cover 7 secured to flanges 8 on the box by bolts 9 to form an airtight compartment. An inlet 10 conducts compressed air into the upper end of one side of the casing and an outlet 11 at the upper end of the opposite

side of the casing allows the ozonized air to 55 pass out of the ozonizer through a pipe (not shown) to the place of use. An air compressor 12 of any suitable construction provided with inlet and discharge valves 13 and 14 delivers compressed air to a pipe 15 communicating with the inlet 10.

Within the casing 6 is a frame of insulating material, such as wood, consisting of side frame members 16, 17, 18 and 19 suitably connected together to form a unit 65 which may be readily placed in or taken out of the casing. The members 16 and 17 are preferably spaced from the sides of the outer casing adjacent thereto. The member 18 is spaced from the side of the casing containing the inlet 10 to form with the casing and member 16 and 17 a channel 20 and its lower end 21 terminates at a distance above the bottom of the casing. The upper end 22 of the member 19 terminates at a distance 75 from the upper end of the casing to form a passage for the flow of ozonized air through the outlet 11. The lower portions of the members 16 and 17 and the bottom of the casing form a channel 23 communicating with the channel 20 and extending from its inlet at the end 21 of the member 18 to the member 19. The channels 20 and 23 form a single channel for conducting the compressed air from the inlet to ozonizing elements 24.

80 The ozonizing elements are in the form of flat plates in which a perforated metal plate or fine mesh wire screen 25 is embedded in or secured between two plates 25' of any 90 dielectric material such as glass. Where plates are used they are secured together by a binder 26 of insulating material. The screen 25 is preferably spaced from the margin of the plates and a conductor 27 leads 95 from one corner to a contact 28.

85 Formed integral with or secured to the frame members 16 and 17 are racks of insulating material, such as wood, having 100 grooves 31. The ozonizing elements are slidably mounted in the racks so as to be readily removable therefrom for the purpose of repair, cleaning or replacement and are held thereby in spaced relation to form 105 passages through which the air passes. The ozonizing elements rest upon contact plates 32 secured to the members 29 and having resilient contact fingers 33 adapted to be en-

gaged by the contacts 28. The plates are held in engagement with the contacts by retainer strips 34 which press upon the upper edges of the plates adjacent the grooves 31 and are removably secured to the upper edges of the racks 29 in any suitable manner, as by screws 35.

Electric current is conducted to alternate ozonizing elements from a conductor 36 carrying a terminal plug 37 secured to a tongue 38 on one of the plates 32 by a bolt 39, the current passing to these elements from the plate 32 and the contacts 28. The circuit is completed through the other units 15 which have their contacts 28 contacting with the other contact plate 32 connected to a return conductor 40 through a tongue on this plate similar to the tongue 38 and a terminal plug 41 similar to the plug 37. Thus, 20 when the current is on, the discharge takes place between the elements and the air passing through the spaces between the elements is subject to this discharge and the oxygen therein is converted to ozone.

25 The racks 29 terminate at a distance from the cover 7 and the members 16, 17 and 18 have an airtight fit with the cover so that a space or chamber is formed above the plates through which the ozonized air passes to the outlet 11. The contact plates 32 are disposed on the same horizontal plane as the lower end 21 of the member 18 and the compressed air passes from the inlet 10 and through the channels 20 and 23 and then 35 directly up through the passages between the spaced ozonizing elements where it is subjected to the electric discharge and thence through the space above the ozonizing elements. By means of the above free circulation of the air through the ozonizer, the elements are kept cool and a large quantity of ozonized air may be efficiently generated.

In the construction shown in Figs. 4, 5 and 6, the outer casing consists of a cylindrical metal shell 43 having flanged ends receiving cover plates 44. Guide rails 47 of insulating material, such as wood, are secured to the shell and a closed box 48 of insulating material, such as wood, is slidably 50 mounted on the guide rails and within the shell as shown in Fig. 6. This box and its parts are the same as the whole structure shown in Fig. 1 except that the casing is of wood or other insulating material 55 and the location of the inlet and outlet is somewhat different. The box carries ozonizing elements 49 like those previously described, which are mounted and supported in the box in a manner similar to the previously described construction and rest upon and are electrically connected to contact plates 50, similar to the plates 32. These contact plates are connected by means of a bolt 51 to a shoe 52. This shoe is adapted 35 to contact with metal rails 53 mounted on

the guide rail 47 and insulated from the outer metal casing. Terminal plugs 54 are connected in circuit with the plates 53 and to a suitable source of current so that current is supplied to the contact plates 50 in a manner similar to that of the first construction. The air is admitted to a channel 55, formed in the box, by means of a nozzle 56 extending down through a flanged opening 57 in the shell and into the box. This nozzle is secured in place by means of a detachable coupling 58 and the compressed air is delivered by the compressor to a pipe 59 which is connected to the nozzle 56 by a coupling 60. The air passes down through the channel 55 into the channel or space 61 in the bottom of the box, thence up between the ozonizing elements into a space 62 at the top of the box, the ozonized air being conducted from the box through a nozzle 63 leading into the top of the box through the shell 43 and connected to the shell and to the outlet pipe 64 in a manner similar to the inlet nozzle previously described. A stop 65 is mounted on the guide rails 47 to limit the inward movement of the box 48 into the shell so that said box may be properly positioned to secure the nozzles in place. With this construction, on the disconnection of the nozzle and a removal of the front head, the box with the ozonizing elements may be withdrawn from the shell for inspection. The top cover 48' of the box is removable, similar to the metal cover 7 of the previous construction, so that the plates may be removed or renewed if required.

From the above description it will be noted that an unobstructed space is provided above and below the plates so that a quantity of air may be passed through the spaces between the plates and be subjected to the discharge from the entire surface of the plates. The space within the frame forms in effect an air conduit with the ozonizing elements disposed in said conduit and spaced from the ends thereof to divide the air into a plurality of streams. The flat plates provide a large discharge surface and may be readily arranged in a given space to handle a greater amount of air and this more efficiently than is possible with the usual tubular form of ozonizing element.

It is to be understood that this invention is not limited to any specific form or arrangement of parts, except in so far as said limitations are specified in the claims.

What I claim as my invention is:

1. In an ozonizing apparatus, the combination of a frame forming an air conduit having an inlet opening and an outlet opening and provided with racks intermediate its ends, contact plates secured to the frame above the inlet opening and below the racks, a plurality of ozonizing elements in the form of flat plates disposed in said racks 125

and supported by said contact plates, each of said elements having a contact engaging one of the plates.

2. In an ozonizing apparatus, the combination of a frame forming an air conduit having inlet and discharge openings and provided with grooved racks intermediate its ends, contact plates secured to the frame above the inlet opening and having resilient contact fingers in line with the grooves in the rack, a plurality of ozonizing elements in the form of flat plates disposed in said racks and engaging said fingers, each of said elements having a contact resting on

10 a contact finger on one of the plates, and means for supplying compressed air to the inlet of said conduit.

3. In an ozonizing apparatus, the combination of a frame forming an air conduit having inlet and discharge openings, a plurality of spaced apart flat plate ozonizing elements arranged in a row across the conduit and spaced from its ends, contact plates engaging said elements, a closed cylindrical metal casing having longitudinally extending guide strips, and contact plates mounted on said guide strips and electrically connected with said first named contact plates.

4. In an ozonizing apparatus, the combination of a rectangular casing having an air conduit formed therein, a plurality of ozonizing elements disposed in said conduit between the ends thereof and in spaced relation, a closed cylindrical metal casing having longitudinally extending guide strips for supporting said first named casing within the metal casing, contact members mounted on said guides and electrically connected to said elements, means for conducting air to one end of said conduit, and means for conducting the ozonized air from the other end of the conduit.

izing elements disposed in said conduit between the ends thereof and in spaced relation, a closed cylindrical metal casing having longitudinally extending guide strips 35 for supporting said first named casing within the metal casing, contact members mounted on said guides and electrically connected to said elements, means for conducting air to one end of said conduit, and means for conducting the ozonized air from the other end of the conduit.

5. In an ozonizing apparatus, the combination of a rectangular casing of insulating material having an air conduit formed therein, a plurality of ozonizing elements disposed in said conduit between the ends thereof and in spaced relation, a cylindrical metal shell having longitudinally extending guide strips for supporting the casing, contact strips on said guide strips, contact strips on the outside of said casing slidably engaging said first named contact strips and electrically connected to said elements, and heads closing the ends of said shell. 55

In testimony whereof I affix my signature in presence of two witnesses.

WILLIAM G. LINDEMANN.
